APPARATUS FOR TREATING OILS

Arthur E. Nash, Mount Airy, Philadelphia, Pa.,
assignor to Alcorn Combustion Company, Philadelphia, Pa., a corporation of Delaware

Application May 22, 1935, Serial No. 22,776
Renewed March 11, 1938

3 Claims. (Cl. 196—110)

My invention relates to systems of and apparatus for treating oils, particularly mineral and hydro-carbon oils, especially petroleum, including products or components thereof, for refining, 5 distilling or otherwise treating the oils, more particularly for cracking or converting the higher boiling into lower boiling oils, as in the manufacture of gasolines or other products.

It is the object of my invention to provide for 10 stills or systems for cracking or otherwise heat treating petroleum (which term is here employed in the generic sense to include petroleum and other mineral and hydro-carbon oils, and components or products thereof) tube systems which, 15 particularly for large throughputs, shall, without material or any increase in size or internal diameter of the tubes, avoid excessive pressure drop between the inlet to and outlet from the heating system; in which heat shall be applied 20 to the tubes for the several streams in each bank or zone substantially equally and at maximum rates; in which the number of tubes or total tube length shall be small for the throughputs and heat inputs involved; and which within shall be 25 structurally simple, and low in cost of construction and upkeep.

To these ends, and in accordance with my invention, the petroleum is passed, through one or 30 more heating zones of the heating system in a plurality of parallel streams which are entirely independent of each other between their inlets and outlets to and from such zone or zones, in tubes disposed in a single row or tier in which the tubes for the different streams alternate with 35 each other, so insuring in each zone or tube bank substantially identical heating effects upon the petroleum in the several streams.

Further in accordance with my invention, the tubes for each stream of petroleum are, to permit the tubes for the different streams to be disposed 40 in a single row, at their ends on the exterior of the furnace provided with fittings including tubular bends or connections offset with respect to tubes for the other stream or streams; 45 and further in accordance with my invention the fittings for each pair of neighboring tubes of each stream are locked to each other either immediately, or through or to a fitting of an intervening tube of another of the streams.

In connection with broader aspects of the present invention, reference may be had to copending applications, Serial No. 164,682, filed January 31, 1927, of Nash and Alcorn for "Heat transfer system"; Serial No. 497,553, filed November 22, 55 1930, of Frank H. Praeger, for "Heat transfer

system"; and to Serial No. 721,480, filed April 20, 1934, of Nash and Shelly, for "Heat transfer system". I do not herein claim subject matter disclosed or claimed in aforesaid applications, respectively owned by the same assignee as the present invention.

My invention resides in the methods, apparatus, and structural arrangements hereinafter described.

For an understanding of my methods and apparatus, reference is to be had to the accompanying drawings, in which:

Figure 1 is a vertical sectional view, partly in elevation, of a furnace system for practicing my method and embodying one form of my apparatus;

Figs. 1a and 1b are explanatory diagrams;

Fig. 2 is a diagrammatic illustration of a two-stream system in accordance with my invention;

Fig. 3 is an end elevational view of tube connections;

Fig. 4 is a plan view of a portion of the structure of Fig. 3 comprising the fittings of and connection between the neighboring tubes for one stream;

Fig. 5 is an end elevational view of the offset tubular connector member of Figs. 3 and 4;

Fig. 6 is a fragmentary sectional view, on the line 6—6 of Fig. 3;

Fig. 7 is an end elevational view of a modified form of tube connections;

Fig. 8 is a plan view of a portion of the structure shown in Fig. 7;

Fig. 9 is an end elevational view of a portion of the structure of Figs. 7 and 8;

Fig. 10 is an end elevational view, partly in section, of a portion of the structure of Figs. 7 and 8;

Fig. 11 is an end elevational view of a box or solid casting type of tube connecting fitting;

Fig. 12 is a plan view of the structure shown in Fig. 11.

Referring to Fig. 1, illustrating one form of my apparatus suitable for practicing one of my methods, the furnace is of the double ended type, each end preferably provided with means for burning fuel, such as oil or gas in particular, or powdered solid fuel.

In the example illustrated there are provided the heating zones or chambers H and H₁, disposed within end walls 1, 1, floors 2, 2, and roof walls 3, 3, which may be disposed horizontally or in any other suitable relation, or as shown, inclined inwardly and forwardly toward the mid-section 4 of the roof wall structure which, as a

whole, may be supported from the roof truss 5, of structural steel, supported by columns 6.

Between chambers H and H¹ is disposed a third chamber H², open at its top and bounded at each side by a bridge wall comprising the walls 7 and 7^a spaced from each other and supported or held by the metal columns 8 disposed in the interspace, and covered with refractory structures 9, 9.

10 With each of the heating chambers H and H¹ is associated a plurality of muffles or combustion chambers M and M¹ disposed side by side in horizontal array, and each provided with a fuel burner 10 provided with valve 11 for controlling 15 as to each muffle or combustion chamber M and M¹ the rate of combustion or amount of fuel burned, for controlling the input of heat into the furnace system.

16 In the muffles M, M¹ combustion may be substantially completed, in which case there are discharged into the chambers H and H¹ products of combustion; or the discharge from the muffles when combustion therein is not completed may be flames or burning mixtures of fuel and air; 20 all for brevity termed herein "combustion gases".

25 These gases, as they issue from the muffles and as they pass over and above the floor tubes, are incandescent or of such high temperature that they may be classed as radiant, causing, if desired, the side walls and bridge walls to become incandescent or radiant, thereby radiantly to heat any of the tube structure within radiant view thereof.

30 The petroleum charged into the system is delivered through pipe 12 to the pump P, controllable as to speed or output, which forces it in two streams at suitable pressure through the pipe connections 13, 14, controlled respectively by valves 15, 16, to the groups of tubes T and T¹, 35 all in series with each other within each group. The one stream S, that passed through the group of tubes T, enters, as indicated by the arrows, the first tube T² of the bank of tubes adjacent the floor 2 of chamber H.

40 The stream S passes in succession through alternate of the tubes T² which at opposite ends of the furnace, on the exterior thereof, are connected to each other by the tubular connectors C which, as hereinafter described, are offset connector bends, crossing over or jumping the intermediate tubes of the other stream.

45 The second stream S¹ similarly passes through the group of tubes T¹ in chamber H² and thence, as indicated by the arrows, to the tube T³, the first at the left end of the floor tube bank in chamber H, and thence through the remainder of the tubes T³ of that bank alternating with the aforesaid tubes T², and similarly, on the exterior of the furnace at opposite ends thereof cross-connected by their tube connectors C¹.

50 The streams S and S¹ leaving the last tubes T² and T³ at the left of the floor bank in chamber H, traverse, respectively, the tubes T⁴ and T⁵ of the roof bank in chamber H, then tubes T⁶ and T⁷ of the roof bank in chamber H¹, and finally the tubes T⁸ and T⁹ of the floor bank in chamber H¹.

55 The two streams pass out of the furnace system through the outlet pipes 17 and 18, which may be controlled respectively by valves 19 and 20, for further treatment separately or as indicated combined into a single stream passing through pipe 21, for any suitable further step of the refinery process, such, for example, as may be effected in a reaction chamber, soakage cham-

ber, fractionating system, etc., to which the line 21 may connect either directly or indirectly through one or more other process zones, as well understood in oil refining in general and in petroleum cracking in particular.

60 The temperature of the oil charged into the system, and the temperatures of the two streams S and S¹ at their outlets from the system may be indicated or recorded by any suitable pyrometric apparatus, including, for example, thermocouple J at the inlet to the system and thermocouples J¹ and J² adjacent the discharge ends of the streams. The rise in temperature of stream S is indicated or recorded by the difference in electromotive forces produced by the thermocouples J and J¹, and the rise in temperature of stream S¹ by the difference between the electromotive-forces produced by the thermocouples J and J².

65 The floor tubes T² and T³ in the chamber H and T⁸ and T⁹ in chamber H¹ are disposed beneath and outside of the current of combustion gases discharged by the muffles M and M¹ to the end that the floor tubes shall be heated preponderantly or substantially entirely by radiation directly from the combustion gases and to some extent from radiant walls, with application of heat to the floor tubes by convection to a relatively unimportant extent.

70 The roof tubes T⁴ and T⁵ in chamber H and T⁶ and T⁷ in chamber H¹ are heated by radiation from gases and walls, and, depending upon their relations to the currents of combustion gases, either substantially or insubstantially by convection.

75 The combustion gases in traversing the heating zones H and H¹ pass inwardly and upwardly therein, over the tops of the bridge walls, and thence downwardly in a common gas current through the chamber H², the gases sweeping the tubes T and T¹ in contact therewith, so heating them by convection, and those tubes, except as to the uppermost rows, are heated little, if at all, by radiation; the gases pass from the lower part of chamber H² to stack.

80 The sequence of traverse of the several tube banks or heating zones by the independent streams of petroleum may be anything suitable or desirable; the sequence indicated in Fig. 1 is suitable, and in some instances preferred, particularly for cracking petroleum to produce lower boiling products, such as gasolines or the like.

85 Generally, and as indicated by Fig. 1, the charging stock is the same in both streams which are subjected preferably to substantially identical heat treatments in each zone and throughout the system of furnace zones with consequent substantially identical effects upon the oil in the different streams. Usually it is desirable that the temperatures of the streams at their outlets from the furnace system shall be equal, the several streams having under such circumstances been raised in temperature to like extents above the inlet temperature as determinable by the aforesaid pyrometers. The rise in temperature of the oil in each stream is dependent upon the heat input into the furnace system, controllable by valves 19 or otherwise, and by the rate of flow of the oil in the stream. With equal rates of flow in the several streams, other things being the same, their changes in temperature between inlet to and outlet from the system will be equal. Assuming the valves 19, 20 to be omitted, as they may be, the valves 15 and 16 may be adjusted to procure equal rates of flow in the different

streams, by setting them manually, or automatically under the control of the pyrometers for each stream. Or this adjustment to equality of the rates of flow in the streams may be effected by 5 the valves 19 and 20 if valves 15 and 16 are omitted, as they may be. In any event the adjustment of the rates of flow in the different streams may be such that the temperatures of the different streams at their outlets from the 10 furnace system shall be equal, the indications of these temperatures serving as information for either manual or automatic adjustment of the valves. The outlet temperatures of the streams are generally to be held at predetermined magnitudes, for which purpose the valves may be adjusted to procure rates of flow which will procure that predetermined outlet temperature for each stream. Equality in outlet temperatures of the 15 different streams is determinable by setting of 20 the valves as aforesaid and the magnitude of the outlet temperature is determinable in addition by the control of heat input into the system.

When the total lengths of the tubes for the different streams are alike, and their bores have 25 equal cross sections, the rates of flow in the different streams will be substantially equal when the drops in pressure between the inlets and outlets are equal. When, as aforesaid, the total lengths 30 of the tubes and their internal diameters for the different streams are the same, with the same inlet pressure the rates of flow in the different streams will be the same without need for either valves 15, 16 or 19, 20, variation in speed of the pump P then sufficing to determine the rate of 35 flow in each stream such that the temperatures of the streams at their outlets shall be equal.

Particularly in cracking petroleum the similar effects upon the different streams of oil in the furnace system may consist in raising oil to 40 cracking temperature, the cracking then to take place in a reaction chamber or elsewhere in the system, or may consist in partially cracking the oil within the furnace system with completion in a reaction zone or other process step of the 45 system, or may consist in effecting all of the cracking action within the furnace system. And for these purposes the oil may remain in liquid phase throughout the entire furnace system, or may be in liquid phase through part of the system 50 and in vapor phase in another portion thereof, or in vapor phase throughout the furnace system.

Each of the streams is maintainable in the furnace system at suitable pressure above atmosphere, generally at high superatmospheric pressure, 55 independently of the rate of flow in the streams as by valves 19, 20 suitably adjusted to procure the desired super-atmospheric pressure at the outlet of the furnace system; the valves 15 and 16, if present, serving then mainly to determine the rates of flow in each stream. Or in the absence of valves 15 and 16, the speed of pump P may be so adjusted that with the drop in pressure in each stream there is still maintained at its outlet the desired super-atmospheric pressure. 60

In a system such as exemplified by Fig. 1, the rates of flow and exit temperatures of the different streams may be unequal, though with the same charging stock in the several streams such 65 conditions would not ordinarily be desirable. Different rates of flow in the different streams, or a predetermined ratio of the rate of flow in one stream to that in the other, generally may be procured by suitable adjustment of either of the 70 valves 15 or 16, both of which may be provided,

but only one of which is necessary for this purpose.

While in general valves 15, 16 and 19, 20 may all be omitted, nevertheless their presence affords greater freedom and variety of controls. 5

When charging stocks of different ranges of boiling points or other characteristics are charged to the different streams in a furnace exemplified by Fig. 1 as to tube arrangement, as when the tubes are in a single row and the tubes of the 10 different streams alternate with each other, an arrangement exemplified by Fig. 2 may be employed.

In this case a pump P is provided for each of the streams S and S1, which again shall be understood to be within a furnace heating system F, of the character aforesaid, exemplified by Fig. 1. The rate of flow of stream S may be controlled by the valve 15 and the rate of flow of stream S1 may be controlled by the valve 16. Pressure controlling valves 19 and 20 may also be employed, principally to determine at what superatmospheric pressure the oil in the several streams shall be maintained while in the furnace F. The streams may, as indicated, be combined and delivered into a chamber R for effecting some other step in the general process; for this purpose R may be a reaction chamber, a soakage chamber, or the like. Where the pressure in chamber R is to be controlled there may be provided for that 30 purpose an outlet valve 22, which, in the absence of valves 19 and 20 may control the magnitude of super-atmospheric pressure of the streams within the furnace F, or the valves 19 and 20 may effect a lower pressure in the chamber R which may, 35 nevertheless, be super-atmospheric to such degree as determined by valve 22.

With different rates of flow of the different charging stocks in the different streams, the exit temperatures may be substantially equal, though 40 generally may or will be different. For determining the temperature rise in the stream S there may be employed, as before, pyrometer or thermocouple J3 at the inlet and J4 at the outlet; and for stream S1 pyrometer J5 at the inlet and 45 J6 at the outlet.

The arrangement of the tubes of a bank or zone all in a single row or tier is contrasted with the tube arrangements diagrammatically indicated in Figs. 1a and 1b, in which, either for a 50 single stream or a plurality of streams they are disposed in two tiers or rows.

In Fig. 1a the tubes in the upper row are staggered with respect to, or disposed above the interspaces between, the tubes of the lower row. 55 In such arrangement the tubes of the lower or back row, which is farther from the source of heat than the upper or front row, receive less heat per square foot of heating surface than the tubes in the upper row.

In Fig. 1b the tubes in the front or upper row are practically directly above the tubes of the lower or back row; and for a two-stream system the tubes are connected criss-cross as indicated. In this case the lower or back row does not absorb more than approximately half the amount of heat per square foot of heating surface absorbed by the tubes in the upper row. 60

As compared with the arrangements of Figs. 1a and 1b, disposition of the tubes in a single 70 row provides a much greater or maximum application of heat per unit area of heat absorbing surface, with the result that, for a given total heat input to a tube bank, the number of tubes or total tube length, when arranged in a single row, 75

is less than in the case of either Fig. 1a or Fig. 1b. So requiring for a given heat input less tube material, there results from the single row arrangement a saving in cost, which is of particular significance when the tubes are composed of alloy steels or other high cost materials. In addition, the pressure drop between the inlet and outlets of the single row structure is, for a given rate of flow of petroleum, substantially decreased; or for the same pressure drop a greater throughput is possible.

By employing instead of a single stream, through the same tube length which would involve prohibitive pressure differential between inlet and outlet particularly in the case of very large throughputs, the division of the throughput into several parallel streams or flows avoids substantial or any increase in the pressure drop without recourse to tubes of greater than usual size or internal diameter, and by alternating the tubes for the different streams in a single row substantially identical and maximum heat inputs to the separate streams are procured, and the heat is evenly applied to and throughout the several streams.

To employ a single stream tube system for the greater throughputs without increase in pressure drop, involves tubes of prohibitively or undesirably large size or internal diameter.

By way of example merely, and without limitation of my invention thereto, in a system of the character illustrated in Fig. 1, having a throughput of 20,000 barrels of petroleum per twenty-four hours, and a total heat input of 75,000,000 B. t. u.'s per hour, the arrangement may be as follows: Twenty muffles M and twenty muffles M₁, disposed side by side, for tube lengths of 40 feet, all tubes 5 1/4 inches external and 4 inches internal diameter (steel alloy 4% to 6% chromium, 0.5% molybdenum and 0.15% carbon maximum); neighboring tubes in all zones, except H₂, spaced 10 inches between centers, and somewhat closer spacing in zone H₂; fifteen tubes for each stream, thirty tubes total, in each of the roof banks; and ten tubes for each stream, twenty tubes total for each floor tube bank.

By way of example, when the required throughput and the practical limit in tube diameter results in an equivalent cold oil velocity of or in excess of say ten feet per second, recourse to multiple streams with the tubes therefor alternating and disposed in a single row is usually of advantage.

When the tubes are disposed as described in a single row and alternating for the different streams, the cross connection at the exterior of the furnace from a tube of one stream, to the neighboring tube of the same stream, while crossing over or jumping the intervening tube of another stream, fittings of the character generally exemplified by Figs. 3 to 12, inclusive, are provided.

Referring to Figs. 3 to 6, inclusive, the ends of neighboring tubes T₂, of the floor bank in chamber H for example, are rolled or otherwise secured in fittings or housing members 23 between which is the fitting or housing member 23a (Fig. 6) in which is rolled or secured the intervening tube T₃ of the other stream. From each fitting tube T₃ or housing member projects a bracket 24 parallel to the tubes, provided with slots, closed at their upper ends, for receiving the clamps 25 through which extend the set screws 26 which thrust upon the lugs 27 of the tubular cross-connectors C or C₁, each tapered at its inner end

as indicated at 28 to fit a correspondingly tapered surface in members 23. The pressure exerted by screws 26 form at the tapered ends 28 pressure tight connections between the tubes and the cross-connectors C or C₁.

The cross-connector rises from its tapered end 28 in an offsetting arc 29 of about 90° (Fig. 5) and continues in the offset portion 30 to a like arcuate in-turning and descending portion terminating in the tapered end 28 in the fitting of the next tube of the same stream. The offset portion 30 of the connector C passes around or crosses over the fitting of the intervening tube of the other stream, as indicated in Fig. 3. The adjacent connector C₁ is similarly offset and crosses over or jumps the fitting of the tube with which the connector C communicates.

To prevent the tubes from shifting in position when the bends or connectors such as C, C₁ are removed for cleaning them and the furnace tubes, any suitable locking means may be provided.

In the arrangement of Fig. 3, the tube housings or fittings 23 for neighboring tubes T₂ of the same stream are locked, by locking structure 31, to the tube housing of the intervening tube T₃, and accordingly the tube housings for tubes T₂, T₂ are locked to each other indirectly through the intervening tube housing.

To remove the bend or cross-connector C, the set screws 26 are loosened, clamps 25 removed and the connector C then disconnected at its tapered ends 28 from the fittings 23 of the neighboring tubes of one stream, so giving access to them for cleaning, during which they are prevented from shifting by virtue of the aforesaid locking structure.

In Figs. 7 to 10, inclusive, a generally similar offset tube connecting structure is shown. In this case the tubular connector C is arcuate in form, and offset, as more clearly shown in Fig. 9. In this arrangement, Figs. 8, 10, the tube fittings or housings of neighboring tubes of the same stream are locked directly or immediately to each other by structure comprising the plate 32 and upstanding rib 33, with locking bolts 34 locking them at opposite ends to the tube housings or fittings 23.

A similar bend and locking mechanism connects the fittings of the next adjacent tubes in the other stream, each offset bend or cross-connector C and C₁ passing around or jumping the housing for the intervening tube of the other stream.

In Figs. 11 and 12 is shown an offset connector C for neighboring tubes of the same stream, of the box or solid casting type having at the ends the parts 23 in which the tubes are rolled or otherwise connected, and each provided with a screw threaded plug 34 removable for access to the tubes for cleaning. Here again locking structure 35 locks the housings for neighboring tubes of one stream to the housing of the intervening tube of the other stream, comparable to the arrangement of Fig. 3. The connector C₁ serves for neighboring tubes of the other stream, crossing over in offset relation to the intervening tube and housing of the stream traversing connector C.

What I claim is:

1. A system for heating petroleum to cracking temperature comprising a pair of separately fired heating chambers, adjustable burner-means individual thereto for producing in each chamber a current of hot gases, at least two banks of tubes disposed within each chamber in single rows on opposite sides of each said current of gases, means connecting alternate tubes of each said

- banks in series for passage therethrough of separate streams of petroleum, means connecting said banks of both chambers for passage of said streams therethrough in succession, supply-means 5 for introducing under super-atmospheric pressure separate streams of petroleum to said connected banks of tubes, separate means for each stream for controlling the magnitudes of the pressures of said streams upon discharge from said banks 10 of tubes, means for adjusting said burner-means to vary the rate of heat absorption by said banks of tubes, and means for each stream responsive to the temperature rise of each stream for determining the setting of said adjusting means, and 15 15 of said pressure-controlling means.
2. A system for heating petroleum to cracking temperature comprising a pair of heating chambers in communication with each other, burner-means for producing currents of combustion gases 20 individual to said chambers, a bank of tubes disposed adjacent the floor of each chamber, a bank of roof tubes disposed adjacent the roof of each chamber, the tubes of each bank disposed in a single row, connections for passage of the petroleum 25 in different streams through alternate tubes of each row and in succession through all of said tube-banks, inlet and outlet valves for each of said streams for controlling respectively the rate of flow and the discharge pressure of each of said streams, and means responsive to the inlet and

outlet temperatures of each stream for determining the setting of said valves to produce a predetermined temperature rise of each of said streams.

3. A system for heating petroleum to cracking 5 temperature comprising a down-draft convection chamber, a bank of tubes therein, a pair of heating chambers disposed, respectively, on opposite sides of said convection chamber and in communication with each other, burner-means for 10 producing currents of combustion gases individual to said chambers, a bank of tubes disposed in a single row adjacent the roof of each of said chambers, a bank of tubes disposed in a single row adjacent the floor of each of said heating chambers and substantially below said burner-means, 15 connections between the tubes of said banks for passage of petroleum in two streams through said convection bank, through alternate tubes, of each row, of one bank of said floor tubes, of both banks 20 of said roof tubes, and of said other bank of said floor tubes, in the order named, inlet and outlet valves for each of said streams for controlling the rate of flow and the discharge pressure of each of said streams, and means responsive to the temperature 25 rise of each stream for determining the setting of said valves to produce a predetermined temperature rise of each of said streams.

ARTHUR E. NASH. 30
